UNITED STATES PATENT OFFICE.

RICHARD K. GREGORY, OF GREENSBORO, NORTH CAROLINA, ASSIGNOR OF ONE-HALF TO JOHN H. WHITE, OF BALTIMORE, MARYLAND.

SURGEON'S KNIFE.

No. 878,524.

Specification of Letters Patent.

Patented Feb. 11, 1908.

Application filed September 24, 1907. Serial No. 394,380.

To all whom it may concern:

Be it known that I, RICHARD K. GREGORY, citizen of the United States, residing at Greensboro, in the county of Guilford and 5 State of North Carolina, have invented certain new and useful Improvements in Surgeons' Knives, of which the following is a specification.

This invention comprehends certain new 10 and useful improvements in surgical instruments, and the invention has for its object an improved and efficient construction of surgeons' knife the use of which will establish and maintain aseptic conditions.

15 With this and other objects in view as will more fully appear as the description proceeds, my invention consists essentially in a surgeon's knife embodying a reservoir for fluids of an antiseptic, anesthetic, hemo- 20 static, and styptic character, means being provided for permitting the fluid or fluids contained in the reservoir to flow therefrom along both sides of the blade during the operation so that the incision or wound may 25 be instantly treated and the liability to blood-poisoning effectually precluded.

A further object of the invention is a knife 30 of this character the construction of which insures that the desired fluid will be spread evenly or to the best possible advantage over 35 the blade and in which the flow may be easily regulated and controlled, and to this end the invention also consists in certain constructions and arrangements of the parts that I shall hereinafter fully describe and claim.

For a full understanding of the invention, reference is to be had to the following description and accompanying drawings, in 40 which:

Figure 1 is a perspective view of my improved knife for surgeon's use; Fig. 2 is a longitudinal sectional view; and, Fig. 3 is a sectional side elevation.

45 Corresponding and like parts are referred to in the following description and indicated in all the views of the drawings by the same reference characters.

Referring to the drawings, the numeral 1 50 designates the blade, and 2 the handle of a surgeon's knife constructed in accordance with the principles of my invention. The handle 2 is hollow, as shown, and is provided at one end with a filling tube or bead 3 in 55 which the screw-cap 4 or other suitable

closure fits, a gasket or washer 4^a being preferably interposed between the rim of the tube and the milled head of the cap.

At the juncture of the blade with the handle the knife is formed with a neck portion 5 which fits within one end of the handle and is held therein by a pin 5^a or the like and which is preferably substantially flat on both faces and of slightly greater thickness than the blade, said neck being formed with 60 shoulders 6 as shown.

The neck portion 5 is formed with ports 7 establishing communication between the blade and the interior of the handle or reservoir constituted thereby. Main channels 8 70 extend toward the blade from said ports, and thereby form openings leading from the interior of the reservoir to the blade, said channels being formed with divergent branches 9 terminating in the blade.

A valve 10, which may be a turning plug valve, as shown, is mounted in the hollow handle 2 so as to enable the operator to control or altogether shut off the flow of liquid, and preferably this valve is mounted close to 80 the blade, or at the front portion of the handle, where the operator may use a finger and thumb of the hand that is holding the knife, to turn or operate the valve. Preferably the handle is depressed on both sides where 85 the valve is located.

From the foregoing description in connection with the accompanying drawings, it will be seen that I have provided a very simple and efficient surgeon's knife the numerous advantages of which will be readily apparent to surgeons and others skilled in the art to which this invention appertains, in addition to the advantages set forth at the outset of the specification as objects which it 90 is the purpose of my invention to attain.

Having thus described the invention, what is claimed as new is:

1. A knife of the character described, comprising a blade, and a handle, said handle being hollow and constituting a reservoir, the knife being provided with an opening leading from the interior of the reservoir to the exterior of the blade.

2. A knife of the character described, comprising a blade and a hollow handle, the knife being provided with an opening leading from the interior of the handle to the exterior of the blade, and a valve mounted in the handle.

3. A knife of the character described, com-

prising a blade and a hollow handle, the knife being provided with ports and channels leading from said ports to the blade, said ports and channels establishing communication between the interior of the reservoir and the exterior of the blade.

4. A knife of the character described, comprising a blade and a hollow handle, the knife being provided with ports and channels leading from said ports and establishing communication between the interior of the handle and the exterior of the blade, said channels being provided next to the blade with divergent branches.
- 10 5. A knife of the character described, comprising a blade and a hollow handle, and a neck portion between the two, said neck portion being formed with shoulders and with

ports in said shoulders establishing communication with the interior of the reservoir 20 and the exterior of the neck portion, said neck portion being also formed with channels leading towards the blade from said ports.

6. A knife of the character described, comprising a blade and a hollow handle, the knife being provided with an opening leading from the interior of the handle to the exterior of the blade, and a valve mounted in the handle at the blade end thereof.

In testimony whereof I affix my signature in presence of two witnesses.

RICHARD K. GREGORY. [L. s.]
